FUEL INJECTOR PUMP

Olof Ljungstrom, Detroit, Mich.

Application December 13, 1937, Serial No. 179,584

8 Claims. (Cl. 103—37)

This invention relates generally to pumps and refers more particularly to fuel injector pumps for internal combustion engines.

One of the principal objects of this invention consists in the provision of a dependable relatively simple and highly effective fuel pump composed of a comparatively few parts capable of being inexpensively manufactured, assembled, and installed.

Another advantageous feature of this invention resides in the provision of a fuel injector pump of the reciprocating plunger type having improved means for adjusting the effective stroke of the plunger to vary the volume of fuel injected and having means operable independently of the aforesaid means for initially predetermined the effective stroke of the plunger. This latter feature is of prime importance in multi-cylinder internal combustion engines where a separate injector is provided for each cylinder, since it offers the possibility of individually adjusting the plunger of each pump so that the latter will provide a uniform quantity of fuel in each cylinder.

A further object of the present invention resides in the provision of a fuel injector pump of the character set forth wherein the plunger is carried by a reciprocable member having a constant stroke and thereby capable of being operated by a cam driven from one of the engine shafts.

The foregoing, as well as other objects, will be made more apparent as this description proceeds, especially when considered in connection with the accompanying drawing, wherein:

Figure 1 is a longitudinal sectional view through a fuel injector pump constructed in accordance with this invention;

Figure 2 is a cross sectional view taken substantially on the plane indicated by the line 2—2 of Figure 1; and

Figure 3 is a cross sectional view taken substantially on the plane indicated by the line 3—3 of Figure 1.

Referring now to the drawing, it will be noted that there is illustrated in Figure 1 a fuel injector pump of the plunger type having a cylinder 10 closed at one end by means of a head 11 and at the opposite end by means of a reciprocable piston 12. The end of the cylinder 10 adjacent the head 11 is provided with a radially outwardly extending flange 13 removably clamped to a corresponding flange 14 on the head by means of the fastener elements 15 which also function to se-

cure the injector on the supporting structure 16, shown in Figure 1 by the dot and dash lines.

The head 11 is provided with a laterally directed fuel intake passage 17 communicating with a source of fuel under pressure (not shown) and also communicating with a bore 18 formed in the head on the axis of the cylinder 10. The bore 18 is provided with a reduced axially extending discharge passage 19 having an annular recess 20 in the side wall thereof forming an annular valve seat 21 for engagement with the head 22 of a valve member 23. The valve member 23 is in the form of a relatively light sleeve reciprocably mounted in the reduced portion 19 of the bore 18, and the head 22 of the valve member cooperates with the adjacent end of the plunger 24 to form a fuel receiving chamber 25.

Upon reference to Figure 1, it will be noted that the side walls of the valve member are provided with angularly spaced openings 26 adjacent the head 22. The purpose of these openings is to permit fuel to flow from the chamber 25 into the valve member, when the latter is retracted from its seat by the pressure produced in the chamber 25 by movement of the plunger toward the head 22 of the valve member. The fuel entering the valve member under pressure flows axially through the latter out of the discharge opening 27 in the head. It will be observed from Figure 1 that the valve member is yieldably urged in a direction to engage the head 22 thereof with its seat 21 by means of a coil spring 28 housed in the valve member with one end abutting a shoulder 29 extending radially inwardly from the side walls of the valve member and with the other end engaging an adjustable abutment 30.

The abutment 30 is threaded in the discharge opening 27 of the head and is centrally apertured, as at 31, to permit the passage of the fuel therethrough. The abutment 30 also acts as a stop to limit movement of the valve member in a direction away from its seat and is so located in the bore 18 to stop the valve member before the openings 26 move out of communication with the annular recess 20.

The flow of fuel under pressure from the passage 17 into the chamber 25 is controlled by the plunger 24 mounted in the sleeve 32 for reciprocation axially of the cylinder 10. Upon reference to Figure 1, it will be noted that the outer end of the sleeve 32 has a pressed fit within the enlarged portion of the bore 18 and seats against an annular shoulder 33 formed by the reduced portion 19 of the bore 18 between the valve member 23 and the fuel intake passage 17. The ex-

treme outer end of the sleeve is counterbored to form an enlarged chamber 34 around the plunger 24, and this chamber communicates with the intake passage 17 through the medium of an opening 35. The space between the side walls of the chamber 34 and the outer end portion of the plunger 24 is closed by means of a bushing 36 having a pressed fit within the outer end of the chamber 34 beyond the opening 35 and having a sliding engagement with the plunger. With the above construction, it will be noted that when the plunger 24 is in the position thereof shown in Figure 1, the fuel under pressure in the passage 17 is prevented from entering the chamber 25 and is confined to the chamber 34 until the plunger has been retracted to its dotted line position, illustrated in Figure 1, wherein communication is established between the passage 17 and chamber 25. In this connection, it is to be noted that the strength of the spring 28 acting on the valve member 23 is sufficiently greater than the normal pressure of the fuel in the supply passage 17 to maintain the valve closed until the plunger commences its working stroke.

In order to reduce the weight of the fuel injector to the minimum, the plunger 24 is shown herein as being formed of hollow tubing drawn, or otherwise suitably fashioned to the contour shown. The outer or working end of the plunger is, of course, closed to impart the pressure on the fuel in the chamber 25 required to open the valve member 28 and eject the fuel through the discharge opening 27. The contacting surfaces of the plunger and sleeve may be lubricated from the pressure feed of the engine (not shown) through the medium of a radial passage 38 formed in the head 11 and having the radially inner end communicating with the recess 39 formed in the sleeve 32 around the plunger 24.

The quantity of fuel ejected through the discharge opening 27 by the plunger 24, of course, depends upon the displacement of the chamber 25, and this displacement may be varied by altering the effective stroke of the plunger. The plunger 24 is operatively connected to the piston 12 for reciprocation by the latter, and this connection is capable of adjustment to vary the position of the outer end of the plunger with respect to the head 22 of the valve 23. In other words, the capacity of the chamber 25 is increased, or reduced, by adjusting the connection between the piston 12 and plunger 24 to locate the latter farther from or closer to the valve 23.

The above adjustment is accomplished without disturbing the stroke of the piston 12 and, in the present instance, the latter is reciprocated axially of the cylinder by means of a cam 40 mounted upon a shaft 41, which is driven by the motor (not shown). The cam 40 is engaged by a roller 42 rotatably supported on a pin 43 extending transversely through the head 44 of the piston and having one end extending beyond the adjacent side wall of the piston for engagement in an axially extending recess 45 formed in the cylinder wall. The projecting end of the pin 43 forms a key, and the recess 45 forms a keyway which cooperates with the key to permit axial sliding movement of the piston, but to prevent rotation of the latter.

The adjustable connection between the piston 12 and plunger 24 includes an internally threaded sleeve 47 having a reduced annular portion 48 journaled in the adjacent end of the piston and forming a radially extending shoulder engageable with a radially extending flange 46 on the piston

for receiving a driving thrust from the latter. Threaded within the opposite end of the sleeve is a tubular member 49 having a portion 50 forming an axial extension of the sleeve 47 and having a flange 51 extending radially inwardly from the end thereof adjacent the sleeve. The flange 51 forms an abutment for engaging a radially outwardly extending flange 52 on the adjacent end of the plunger 24, and the two flanges are normally yieldably maintained into engagement with each other by means of a coil spring 53 which surrounds both the plunger and its supporting sleeve 32. One end of the spring 53 abuts the head 11, and the opposite end of the spring engages the radial flange 52 on the end of the plunger adjacent the piston to not only maintain the same in contact with the flange 51 on the tubular member 49, but to also urge the sleeve 47 into engagement with the piston 12. Thus, from the foregoing, it will be noted that the plunger 24 is moved in a direction to force fluid from the chamber 25 past the valve member 23 when the piston 12 is moved in a corresponding direction by the cam 40, and both the plunger and piston are retracted, or moved, in the opposite direction by the spring 53. In other words, the spring 53 maintains the follower or roller 42 in frictional engagement with the cam 40 so that the actual stroke of the plunger is constant and depends upon the throw of the cam 40.

However, it has been stated above that the effective stroke of the plunger, or the capacity of the fuel chamber 25, may be varied by adjusting the operative connection between the plunger and the piston 12. In general, the above is accomplished by rotating the internally threaded sleeve 47 relative to the externally threaded tubular member 49, so as to either increase, or decrease, the capacity of the chamber 25. In other words, rotation of the internally threaded sleeve in one direction causes the tubular member 49 to move outwardly relative to the sleeve and effects a movement of the free end of the plunger toward the head 22 of the valve member 23 to decrease the capacity of the chamber 25. On the other hand, movement of the internally threaded sleeve 47 in the opposite direction causes the tubular member 49 to move axially relative to the sleeve in a direction toward the piston 12 and thereby increases the capacity of the chamber 25.

In detail, the internally threaded sleeve 47 is provided on its external surface with a series of angularly spaced axially extending teeth or splines 55 adapted to mesh with correspondingly spaced splines 56 formed on the inner surface of a revoluble sleeve 57. The sleeve 57 rotatably engages the inner side walls of the cylinder 18 and has a reduced portion 58 journaled on the piston 12. This reduced portion is fashioned to form a beveled pinion having teeth 60 adapted to mesh with corresponding teeth 61 on a ring gear 62 which is rotated in either direction by the throttle control (not shown) in any suitable manner. The tubular member 49 is normally held from rotation in a manner to be more fully hereinafter described so that rotation of the sleeve 57 by the segment 62 effects a corresponding rotation of the internally threaded sleeve 47 relative to the externally threaded tubular member 49 to either increase or decrease the capacity of the chamber 25 depending, of course, upon the direction of rotation of the sleeve 47.

It has been stated above that the tubular member 49 is normally held against rotation in the cylinder, and this is accomplished by forming a

series of angularly spaced axially extending teeth or splines 63 on the external surface of the portion 50 of the member 49 and by engaging these splines with correspondingly spaced splines 64 on the internal surface of a sleeve 65 rotatably mounted in the cylinder 10. As shown in Figure 2, the sleeve 65 is formed with a series of external teeth 66 on the end thereof adjacent the head 11, and these teeth mesh with a suitable pinion 67 having a shaft 68 journalled in the head 11. A set screw 69 is threaded in the pump head and engages the pinion shaft 68 so as to normally prevent rotation of the latter and tubular member 49. However, when it is desired to initially adjust the effective stroke of the plunger 24, or the volume of the chamber 25, the set screw 69 is released from the shaft 68 and the pinion 67 is rotated to impart a rotative movement to the tubular member 49 through the tube 65. It will, of course, be understood that during this initial adjustment of the injector pump, the internally threaded sleeve 47 is held from rotation by the ring gear 62. Thus, it will be noted that rotation of the pinion 67 also effects an axial displacement of the plunger 24 to vary the capacity of the chamber 25 and by reason of this construction, all of the injectors in a multi-cylinder engine may be adjusted to inject a uniform charge of fuel in each of the several cylinders.

It may be pointed out at this time that the fuel injector is preferably supported on the engine in the region of the lubricant reservoir so as to be in the path of the fumes escaping from the reservoir. These fumes are relied upon to a great extent in supplying the necessary lubrication of the various parts of the injector and, for this reason, the cylinder 10, piston 12, sleeve 47, and tube 65 are apertured, as at 10, to permit entrance of the fumes into the cylinder. Also, the openings 10 contribute materially to reducing the weight of the injector to the minimum and this is, of course, desirable from the standpoint of performance and cost of manufacture.

What I claim as my invention is:

1. In a fuel injector of the displacement type having an intake opening for fuel, a reciprocable plunger for displacing the fuel and acting as a slide valve to control the intake port, a reciprocable member coaxially arranged with respect to the plunger, a sleeve carried by the reciprocable member and rotatable relative thereto, a tubular member carried by the plunger and rotatable relative to the latter, said tubular member having a portion threadedly engaging the sleeve, means for rotating the sleeve relative to the tubular member to adjust the stroke of the plunger, and separate means for rotating the tubular member relative to the sleeve to initially determine the effective stroke of the plunger.

2. In a fuel injector of the displacement type having an intake opening for fuel, a reciprocable plunger for displacing the fuel and also acting as a slide valve to control the intake opening, a reciprocable member coaxially arranged with respect to the plunger and having a constant stroke, a revoluble sleeve movable with the reciprocable member and positioned between the latter and plunger, a rotatable member movable with the plunger and having a threaded engagement with the sleeve, a second sleeve rotatable relative to the first sleeve and having teeth meshing with corresponding teeth on the rotatable member, and means for rotating the second sleeve to adjust the effective stroke of the plunger.

3. In a fuel injector of the displacement type

having an intake opening for fuel, a reciprocable plunger for displacing the fuel and also acting as a slide valve to control the intake opening, a reciprocable element coaxially arranged with respect to the plunger and having a constant stroke, a member movable with the reciprocable element and supported for rotation, a second revoluble member movable with the plunger and threadedly engaging the first member, a sleeve rotatable relative to the second member and having a series of teeth meshing with corresponding teeth on the first member, means for rotating the sleeve to vary the effective stroke of the plunger, a second sleeve supported for rotation relative to the first member and having a series of teeth meshing with corresponding teeth on the second member, and means for rotating the second sleeve to determine the initial effective stroke of the plunger.

4. In a fuel injector of the displacement type having an intake opening for fuel, a reciprocable plunger for displacing the fuel and also acting as a slide valve to control the intake opening, a reciprocable member coaxially arranged with respect to the plunger and having a constant stroke, a rotatable sleeve concentrically arranged with respect to the plunger and movable with said plunger, a second rotatable sleeve movable with the reciprocable member and having a portion threadedly engaging the first sleeve, a third sleeve concentrically arranged with respect to the first sleeve and keyed to the latter for rotating the same relative to the second sleeve, means accessible exteriorly of the injector for rotating the third sleeve to vary the effective stroke of the plunger, and means also accessible exteriorly of the injector for rotating the second sleeve to vary the effective stroke of the plunger independently of the last named means.

5. In a fuel injector of the displacement type having an intake opening for fuel, a reciprocable plunger for displacing the fuel and also acting as a slide valve to control the intake opening, a reciprocable member coaxially arranged with respect to the plunger and having a constant stroke, a rotatable sleeve concentrically arranged with respect to the plunger and movable with the plunger, a second rotatable sleeve movable with the reciprocable member and threaded on the first sleeve, a third sleeve concentrically arranged with respect to the two above mentioned sleeves and keyed to the second sleeve, means for rotating the third sleeve to vary the effective stroke of the plunger, a fourth sleeve concentrically arranged with respect to the first sleeve in axial alignment with the third sleeve and keyed to the first sleeve, and means for rotating the fourth sleeve to adjust the effective stroke of the plunger independently of the aforesaid means.

6. In a fuel injector of the displacement type having an intake opening for fuel, a reciprocable plunger for displacing the fuel and also acting as a slide valve to control the intake opening, a sleeve revoluble about the axis of the plunger, a reciprocable member having a portion extending into the sleeve and slidably engaging the sleeve, a second sleeve mounted on the reciprocable member within the first sleeve, a connection between the sleeves providing for sliding movement of the second sleeve relative to the first sleeve and preventing relative rotation between the sleeves, means for rotating the first sleeve about the reciprocable member to impart a corresponding rotation to the second sleeve, and means responsive to reciprocation of the

second sleeve by the reciprocable member to impart a corresponding reciprocable movement to the plunger and effective upon rotation of the second sleeve by the first sleeve to adjust the 5 position of the plunger relative to the intake opening and thereby vary the effective stroke of the plunger by the reciprocable member.

7. In a fuel injector of the displacement type having an intake opening for fuel, a reciprocable 10 plunger for displacing the fuel and also acting as a slide valve to control the intake opening, a sleeve revoluble about the axis of the plunger, a reciprocable member having a portion extending into the sleeve and slidably engaging the 15 sleeve, a second sleeve mounted on the reciprocable member within the first sleeve, a connection between the sleeves providing for sliding movement of the second sleeve relative to the first sleeve and preventing relative rotation between 20 the sleeves, means for rotating the first sleeve about the reciprocable member to impart a corresponding rotation to the second sleeve, means responsive to reciprocation of the second sleeve by the reciprocable member to impart a corresponding reciprocable movement to the plunger 25 and effective upon rotation of the second sleeve by the first sleeve to adjust the position of the plunger relative to the intake opening and thereby vary the effective stroke of the plunger by the

reciprocable member, and means for adjusting said last named means independently of said first named sleeve to also vary the effective stroke of the plunger.

8. In a fuel injector of the displacement type 5 having an intake opening for fuel, a reciprocable plunger for displacing the fuel and also acting as a slide valve to control the intake opening, a reciprocable member co-axially arranged with respect to the plunger and having a constant 10 stroke, a sleeve rotatably supported on the reciprocable member, a second sleeve located within the first sleeve and connected to the reciprocable member for movement as a unit with the latter, a connection between the two sleeves preventing 15 rotation of the sleeves relative to each other and permitting reciprocation of the second sleeve relative to the first sleeve, a third sleeve threadedly engaging the second sleeve and having a portion abutting the plunger for moving the latter as a unit with the reciprocable member, means engageable with the third sleeve to hold the latter against rotation with the second sleeve, and means for rotating the first sleeve to effect a corresponding rotation of the second 20 sleeve relative to the third sleeve and thereby adjust the position of the plunger axially with respect to the intake opening.
